UNITED STATES PATENT OFFICE.

JOSEPH FRIEDLANDER, OF NEW YORK, N. Y.

EYEGLASSES.

1,154,241.

Specification of Letters Patent. Patented Sept. 21, 1915.

Application filed March 14, 1910. Serial No. 549,143.

To all whom it may concern:

Be it known that I, JOSEPH FRIEDLANDER, a citizen of the United States, and a resident of the city of New York, borough of Manhattan, in the county and State of New York, have invented new and Improved Eyeglasses, of which the following is a full, clear, and exact description.

This invention relates to eyeglasses, in which spring-controlled nose clips are pivotally secured in place and have associated therewith means by which they can be manually operated, my improvements residing primarily in the means for mounting the nose clips in position, and in controlling their movement.

One object of my invention is to facilitate the adjustment of the tension of the springs which control the pressure of the clips against the nose, whereby the proper adjustment may be made both when assembling the parts and when making changes in the clips or other parts.

A further object is to simplify the structure of the bridge and at the same time to facilitate the removal of the spring with the lever by utilizing a part of the lever which carries the clip or a wall on said lever to effectively conceal and hold the spring.

30 A further object is to more effectively hold the lever and spring in place by detachably telescoping a retaining member with a post which is rigid on the bridge and which rises from a plate portion of the latter.

Other objects and advantages will be set forth more fully hereinafter and the several novel features defined in the claims.

Reference is to be had to the accompanying drawings forming a part of this specification, in which similar characters of reference indicate corresponding parts in all the views, and in which—

Figure 1 is a front elevation of a pair of eyeglasses having an embodiment of my invention applied thereto, parts of the lenses being broken away; Fig. 2 is a perspective view of a lever and a nose clip of my invention; Fig. 3 is a plan view of part of a pair of eyeglasses, showing a lever and a nose clip; Fig. 4 is an enlarged vertical section of a barrel, showing the spring for controlling one of the levers; Fig. 5 is a plan view of a blank from which one of the levers is formed, and having a barrel for a spring associated therewith; Fig. 6 is a

plan view of a part of a lever, detached from the pivot; Fig. 7 is a perspective view of one of the springs; Fig. 8 is a view similar to Fig. 3, showing certain details of modified form; Fig. 9 is a transverse section on the line 9—9 of Fig. 8; and Fig. 10 is a plan view of a lever of modified form.

Before proceeding to a more detailed explanation of my invention, it should be clearly understood that the invention relates solely to the clip and the means for supporting, controlling and operating the same, and that the structural details of the lens mounts form no part of the invention and can be varied in accordance with individual preference and special conditions, without departing from the underlying spirit of the invention.

Referring more particularly to the drawings, I have shown for example, a pair of eyeglasses having a bow or bridge 1, the opposite ends 2 of which extend outwardly in diametrically opposed directions, and are substantially in alinement. The bow, beyond its outwardly extending portions 2, terminates in lens mounts or clamps 31, which carry the lenses 32. The bridge ends have enlargements 3, which carry levers 5. The levers extend horizontally across the terminals, or outwardly extending portions 2 of the bow, and each lever has rigidly secured thereon, or formed integral therewith, a spring chamber preferably in the form of a barrel or cup 4. This is substantially cylindrical in form and extends upwardly from the lever. The enlargements 3 of the bow extensions have posts 6 which are preferably tubular, and extend through central openings 7 of the barrels. Spiral springs 8 are located within the barrels and encompass the posts.

In the form of the invention shown in Figs. 1, 2, 3, 4, 5 and 6, the barrels, at the upper edges are provided with pluralities of notches 9, which receive the upper, extended and laterally disposed extremities 10 of the springs 8. The bottoms of the barrels have cutaway parts 11 through which the lower, extended and laterally disposed ends 12 of the springs pass to enter openings 13 of the extensions 3. The extremities of the springs are thus anchored, and the springs therefore tend to hold the barrels, and the levers associated therewith, in normal position, as will appear more clearly hereinafter.

The levers, at the front ends have laterally

disposed parts of any suitable form, which constitute finger grips 14, by means of which the levers can be manipulated. The springs tend to force the finger grips apart, and correspondingly to advance the opposite ends of the levers toward each other. The opposite ends of the levers carry the nose clips 15, and the springs thus serve to cause the nose clips to grip securely at the bridge of the nose of the wearer of the glasses. By pressing the finger grips between the fingers, the nose clips can be separated, to permit the glasses to be taken from the nose, or to be placed in position in the usual manner and may be of any suitable form.

The posts 6 have heads 17 at the upper ends, which extend laterally toward the walls of the barrels, and are secured upon the posts preferably by means of retaining screws 18. The heads assist in holding the springs in position, and also act as guides for the barrels. They permit the barrels to rotate freely, but prevent lateral and inclined movements of the barrels in the operation of the levers.

The levers 5, at the ends remote from the finger grips may be secured to the clips in any suitable manner. The particular means shown is made the subject matter of a divisional application, Serial No. 618,108, filed March 31, 1911. As illustrated, the levers have extensions 19 connected by reduced necks 20, with extensions 21. A lateral extension 22 is connected with each extension 19, by a reduced neck 23. The extensions 19, 21 and 22 form leaves for the attachment of the nose clips. They are laterally bent so that the leaves 19 and 21 are parallel though spaced, and can receive between them an end 24 of an arm 25 associated with each nose clip 15. The leaves have threaded openings 26 therethrough, which receive a correspondingly threaded retaining screw 27. The leaf 22 is folded back against the leaf 19, and in this way I provide a double depth of an opening 26 for the end of the screw. This insures a substantial depth of threaded opening, and permits the parts to be securely held together by the retaining screw.

The neck 20 has an opening or slot 28, which is formed to receive a stop-projection 29 of the part 24 of the arm 25. The stop 29 limits the pivotal movement of the arm 25, about the screw 27, if the latter is loose. By varying the size of the stop 29, the amount of movement of the arm can be regulated.

The arm 25 has the part 24 laterally offset and disposed at right angles thereto. The arm also has a part 30 disposed at an acute angle, and extending diagonally with respect to the length of the clip 15. It is secured to the clip, near the lower end thereof, as is clearly shown in Fig. 2. The mate-

rial, metal being preferably employed, from which the clips and the arms are formed, permits them to be bent relatively to one another, so that the clips can be adjusted to fit exactly the nose of the wearer of the glasses. The angular disposition of the parts 25 and 30 of the arm, and the diagonal arrangement of the part 30 relative to the clip, facilitates and enlarges the scope of the adjustment of the clips.

In Figs. 8 and 9 I have shown a modified form of connection between the clip and lever and which is also claimed in the divisional application above referred to. In this form I show levers 33^a, similar to the levers 33, as illustrated in Fig. 10. The nose clips 39 have pairs of arms 40 and 41. The arms 40 have extensions 42 and 43 forming leaves provided with threaded openings. The leaf 43 is folded back upon the leaf 42, and both extend at substantially right angles to the clip. The leaf at the end of the arm 41 is spaced from the leaf 42 and is also provided with a threaded opening. The extension 37^a at the end of the lever 33, is received between the leaves 41 and 42, and has an opening through which passes the retaining screw 44 which is located in the threaded openings of the leaves. The levers 33^a have finger grips 36^a, and barrels 38^a in which are mounted the springs 8^a. The upper ends of the springs are located in edge recesses 9^a of the barrels, and the lower ends which extend tangentially from the body of the springs, project through slots 45 in the barrel walls, and have downwardly disposed extremities located in the openings 46 of the bridge extensions 2. The slots 45 are elongated sufficiently to permit the barrels to move freely when the levers are operated. The lower spring ends are introduced into the openings through slots 47 connected with the slots 45, and extending longitudinally of the barrels, to the upper edges thereof. In this way, the lower ends of the springs can be anchored at points outside of the barrels, as is shown most clearly in Fig. 8. It will be understood that the springs are arranged about posts 48 similar to the posts 6. This form of the eyeglasses is substantially a reversal in certain details, of the form shown for example in Fig. 2. In the latter, each lever 5 has the leaves between which the part 24 of the clip-carrying arm is arranged. In the other form, the clips themselves have the leaves between which the parts 37^a at the ends of the levers are positioned.

In Fig. 10 I have shown a modified form of lever 33, having a barrel 34 provided with a central opening 35 to receive a post. At one end, the lever has a finger grip 36, and at the other an extension 37, by means of which it carries the nose clip. The barrel has a slot 38 in the bottom thereof, con-

centric with the opening 35, and serving to permit the engagement of the lower end of the spring with the bridge extension.

In the preferred form of the lever, the 5 cutaway part 11 is connected with the central opening for the post, as is shown in Fig. 6.

Having thus described my invention, I claim as new, and desire to secure by Letters 10 Patent:

1. Eyeglasses having a bridge with lateral extensions, levers pivotally mounted upon said bridge extensions, nose clips associated with said levers, springs controlling said 15 levers to force said clips normally toward each other, and chambers encompassing said springs, each of said springs having an end secured to one of said bridge extensions and an end adjustably secured to one wall of 20 said chambers, whereby the tension of said springs can be varied.

2. Eyeglasses having a bridge, levers pivotally mounted upon said bridge and having chambers therein, springs in said chambers, 25 and secured respectively to said bridge and a wall of said chambers, and nose clips carried by said levers, said chambers having openings to permit said springs to be secured to said bridge.

3. Eyeglasses having a bridge provided 30 with posts, levers having barrels provided with openings movably receiving said posts, nose clips carried by said levers, and springs mounted in said barrels upon said posts, 35 said springs having ends secured to said barrels and ends secured to said bridge, said barrels having openings through which said last-mentioned ends of said springs pass.

4. Eyeglasses having a bridge provided 40 with posts, levers having openings receiving said posts, whereby said levers are pivotally mounted upon said bridge, said levers having walls forming a chamber encircling said posts, and springs mounted upon said 45 posts and adjustably secured to said chambers, said springs having ends secured to said bridge.

5. Eyeglasses having a bridge provided 50 with end extensions having posts, levers pivotally mounted upon said end extensions, by means of said posts, barrels carried by said levers and encompassing said posts, and springs mounted upon said posts and engaging said end extensions and said barrels, said 55 posts having heads extending laterally toward the walls of said barrels.

6. Eyeglasses having a bridge, levers pivotally mounted upon said bridge and having barrels thereon, springs mounted in said 60 barrels and secured thereto, said springs being secured to said bridge, outside of said barrels, and normally forcing said nose clips toward each other.

7. Eyeglasses having a bridge, lenses carried by said bridge, levers pivotally mounted

upon said bridge and having nose clips, barrels carried by said levers and provided with a plurality of recesses, and springs mounted in said barrels and each secured at one end to said bridge, each of said springs having 70 the other end mounted in one of said recesses, whereby said springs can be adjusted to vary the tension thereof.

8. Eyeglasses having a bridge provided with extensions, levers pivotally mounted 75 upon said extensions, and having nose clips and finger grips, barrels carried by said levers, and springs in said barrels, each of said springs having an end secured to one of said barrels, each of said barrels having a 80 slot extending downwardly from the upper edge thereof, and a slot connected with said first slot and arranged in a plane at substantially right angles to the pivotal axis of said barrel, each of said springs having 85 an end extending through one of said last-mentioned slots and secured to one of said bridge extensions outside of said barrel.

9. In eye-glasses, the combination of a bridge, a lever pivoted thereto, and a spring 90 for swinging said lever, a portion of said lever constituting a cup or container for receiving said spring.

10. In eye-glasses, the combination of a bridge, a lever pivoted thereto, and a spring 95 encircling the pivot and tending to swing said lever, a portion of said lever constituting a cup or container to receive and conceal said spring.

11. In eye-glasses, the combination of a 100 bridge, a lever pivoted thereto, and a spring encircling the pivot and tending to swing said lever, a portion of said lever constituting a cup or container to receive and conceal said spring, one end of said spring being 105 secured to said bridge and the opposite end of said spring being secured to the wall of said cup or container at a point spaced from said bridge.

12. In eye-glasses, the combination of a 110 bridge, a vertical pivot extending upwardly therefrom, a lever mounted to swing on said pivot, a cup or container carried by said lever and encircling said pivot below the free end of the latter, and a spring within said cup or container and tending to swing said lever in one direction.

13. In eye-glasses, the combination of a bridge, a post extending therefrom, a lever pivoted upon said post, a spring encircling 115 said post for swinging the lever, a casing carried by said lever and receiving said spring and a washer at the end of said post for engaging with said casing and preventing wobbling of the lever.

14. In eye-glasses, the combination of a bridge, having a post, a lever pivoted to swing about said post as a center, a spring encircling said post intermediate the bridge 120 and the free end of the post, said lever hav-

- ing means engaging with the post adjacent the free end for preventing tilting movement of the lever and for concealing said spring.
- 5 15. In eye-glasses, the combination of a bridge, a lever pivoted thereon, a spring for swinging said lever, and a wall movable with said lever for receiving and concealing said spring.
- 10 16. In eye-glasses, the combination of a bridge, a lever pivoted thereon, a spring for swinging said lever, and a wall movable with said lever for receiving and concealing said spring, said wall having a slot therein 15 to permit the placing of the spring in position.
17. In eye-glasses, the combination of a bridge, a lever pivoted thereon, a spring for swinging said lever, and a wall movable 20 with said lever for receiving and concealing said spring, said wall having a slot extending longitudinally thereof for receiving and retaining one end of the spring.
18. In eye-glasses, the combination of a 25 bridge, a lever pivoted thereon, a spring for swinging said lever, and a wall movable with said lever for receiving and concealing said spring, said wall having a curved slot through which one end of the spring extends and serving to permit the swinging of the lever.
19. In eye-glasses, the combination of a bridge, a pivot post, a lever pivoted on said post and having a portion constituting a 35 cup or casing pierced to permit the entry of the pivot post, and a spring encircling the pivot post and concealed within said cup or casing.
20. In eye-glasses, the combination of a 40 bridge, a lever pivoted thereon, a cup or casing carried by said lever, the wall of said cup or casing toward said bridge being provided with a curved slot, and a spring within said cup or casing and constraining said
- lever, and having one end extending through 45 said slot into engagement with said bridge.
21. In eyeglasses, the combination of a bridge having an upwardly-extending pivot, a lever mounted on said pivot and having a casing concentric with said pivot, a spring 50 within said casing for restraining said lever, and a plurality of separate and independent points of anchorage for one end of the spring, whereby the tension of said spring may be varied.
22. In eyeglasses, the combination of a bridge having an upwardly-extending pivot, a lever mounted on said pivot and having a casing concentric with said pivot, and a 55 spring within said casing for restraining said lever, the wall of said casing having a plurality of recesses therein for securing one end of said spring at a plurality of points.
23. In an eyeglass, the combination with 60 the lenses, the bridge connection and the levers carrying the nose grips, of operating springs for the levers mounted and concealed within said levers, and means for adjusting the tension of said springs.
24. In an eyeglass, the combination with 65 the lenses, the bridge connection and the levers carrying the nose grips, of posts mounted in the bridge connection, operating springs coiled about the posts, means on the 70 levers for concealing the springs, means on the posts to cover the springs and co-operating with the levers to prevent wabbling and means for adjusting the tension of said springs.
- In testimony whereof I have signed my name to this specification in the presence of two subscribing witnesses.
- JOSEPH FRIEDLANDER.
